UNITED STATES PATENT OFFICE.

RALPH FOLSOM, OF PENDLETON, OREGON, ASSIGNOR OF ONE-THIRD TO J. ALLEN FOLSOM AND ONE-THIRD TO HARRY G. BENSON, BOTH OF PENDLETON, OREGON.

DESIGN FOR A COMBINATION CEDAR CHEST AND SETTEE.

Application filed December 19, 1923. Serial No. 8,098. Term of patent 14 years.

To all whom it may concern:

Be it known that I, RALPH FOLSOM, a citizen of the United States, and a resident of Pendleton, in the county of Umatilla and State of Oregon, have invented a new, original, and ornamental Design for a Combination Cedar Chest and Settee, of which the following is a specification, reference

being had to the accompanying drawing, forming a part thereof, wherein the figure is a perspective view of a combination cedar chest and settee embodying my design.

I claim:

The ornamental design for a combination cedar chest and settee substantially as shown.

RALPH FOLSOM.
